UNITED STATES PATENT OFFICE.

WILLIAM R. RAY, OF SAN FRANCISCO, CALIFORNIA.

AUTOMATIC AIR AND OIL REGULATOR FOR ROTARY BURNERS.

1,406,414.

Specification of Letters Patent. Patented Feb. 14, 1922.

Application filed January 28, 1920; Serial No. 354,711.

To all whom it may concern:

Be it known that I, WILLIAM R. RAY, a citizen of the United States, residing at the city and county of San Francisco and State 5 of California, have invented a new and useful Improvement in Automatic Air and Oil Regulators for Rotary Burners, of which the following is a specification.

This invention relates to an automatic air 10 and oil regulator for rotary burners and the like and especially to means for automatically varying the air flow through the burner as the fires are increased or decreased.

15 It is well known that the steam pressure in a boiler changes or fluctuates under variations in load. It is general practice when oil burners are employed to change the oil pressure and thereby the size of the fires 20 under the boilers, such change in the fire increasing or decreasing the furnace temperature and consequently the volume of steam generated. To efficiently burn the changed amount of fuel, it is necessary to 25 change the rate of air flow through the furnace; for instance, by changing the damper opening under the grate bars, or the position of the air regulator at the front of the furnace.

30 One of the objects of the present invention is to provide a simple, substantial and easily installed mechanism whereby the air intake of the burner blower or the furnace front regulator, or both, may be automatically 35 adjusted to vary the air flow through the furnace. Further, to provide means which operates in unison with the burners, or the oil under pressure delivered thereto, so that a proportional supply of air and oil will be 40 maintained at all times.

Another object of the invention is to provide a regulator which is actuated by variations of the oil under pressure delivered to the burner. Further to provide means actuated by the steam pressure of the boiler for 45 automatically varying the oil pressure delivered to the burner.

Further objects will hereinafter appear.

The invention consists of the parts and 50 the construction, combination and arrangement of parts as hereinafter more fully described and claimed, having reference to the accompanying drawings, in which—

Fig. 1 is a front view of a boiler and furnace showing the application of the invention.

Fig. 2 is an enlarged sectional view of the diaphragm actuated valve.

Fig. 3 is a cross section on line 3—3, of 60 Fig. 2.

Fig. 4 is an enlarged sectional view of the draft regulator, showing its connection with the blower intake shutter.

Referring to the drawings in detail, A indicates in general a boiler and 2 the furnace front. Suitably supported with relation to said furnace front is an oil burner 3, the type of burner employed in the present invention being such as shown in my patent entitled "Oil burner," issued November 19, 1918, No. 1,285,376. A burner of this character consists of an electric motor 4, a fan housing, and a rotary atomizer which is secured on the motor shaft and rotated thereby. The fan housing contains a high 75 pressure blower which delivers air to the furnace in close proximity to the rotary atomizer, and it is also provided with an air damper 6 whereby the volume of air admitted to the blower is controlled. The motor 80 shaft is hollow and the oil employed for combustion is delivered through said shaft to the rotary atomizer by means of a pipe 7. This pipe is otherwise connected with a pumping set not here shown which delivers 85 a predetermined quantity of oil under constant pressure.

Placed on the pipe 7 is a diaphragm actuated valve generally indicated at B. This valve is connected with the steam dome of 90 the boiler by means of a pipe 8 and it serves the function of varying the oil pressure in the pipe 7 between the valve B and the burner proper. The diaphragm actuated valve will remain open as long as the pressure in the boiler proper is below a predetermined pressure, and the pressure of the oil delivered to the burner through the pipe 7 will then be at its maximum. The diaphragm valve will, however, automatically 95 close the moment a predetermined steam pressure is obtained in the boiler and the oil supplied through the pipe 7 is then regulated by a by-pass formed in the valve, said by-pass being so regulated that the pressure 100 of the oil in the pipe 7 between the diaphragm valve and the burner will be considerably lowered. In other words, the diaphragm valve serves two functions, that of maintaining a large fire when the boiler 110 pressure is low and a small fire when a predetermined boiler pressure has been reached.

The diaphragm valve is constructed substantially as shown in Figs. 2 and 3. It consists of a casing B, on the upper end of which is mounted a diaphragm 9. This diaphragm is held upon the casing by means of a head member 10, and a chamber is thus formed above the diaphragm to which steam is admitted by means of the pipe 8. Formed integral with or secured to the lower end 10 of the casing B is a valve casing 11, and mounted in said valve casing is a valve 12 which is directly connected with the diaphragm by means of a stem 13. Surrounding the stem 13 is a coil spring 14. This 15 coil spring is interposed between the diaphragm and an adjusting nut 15. Adjustment of this nut increases or decreases the tension on the diaphragm and therefore provides a manual control whereby the movement 20 of the diaphragm valve may be regulated to suit varying boiler pressures. The valve casing 11 is divided into two compartments 16 and 17. The oil from the pumping system enters the chamber 16 and it passes 25 by the valve into the chamber 17 before it enters the pipe 7 and the oil burner connected therewith. The valve 12 either assumes a closed position or an open position, it being open when the boiler pressure is 30 low and closed when the steam in the boiler has reached a predetermined pressure. When the valve 12 is open a big fire is maintained as the oil is permitted to pass freely through the valve and the pipe 7. With the valve 12 35 closed it is obvious that no oil will enter the pipe 7 and the burner connected therewith, and the fire will thus become extinguished unless a by-pass connection is provided. This by-pass is formed in the valve casing 40 11 proper and it is regulated by means of a valve 18. This valve materially restricts the flow of oil through the casing 11 or the chambers 16 and 17 and it therefore reduces the pressure of the oil in the pipe 7. A 45 small fire is therefore maintained when the valve 12 is closed.

From the foregoing description it should be obvious that the oil pressure in the pipe 7 is either high or low. For the purpose of 50 clearly illustrating the present invention, we will assume that the oil pressure in the pipe 7 is 40 pounds when the valve 12 is open and 20 pounds when the oil passes through the by-pass valve 18. As stated in the preamble 55 of this specification one of the main objects is to provide an automatic air damper whereby the air flow through the burner may be varied as the size of the fire is increased or decreased. This is accomplished 60 in the following manner.

Suitably secured with relation to the burner is a draft regulator generally indicated at C. This regulator, (see Fig. 4) 65 consists of a casing 19 in which is mounted a compressible flexible tube 20. One end of

the tube is closed by means of a head member 21 while the opposite end is open and is secured in the upper portion of the casing as at 22. Formed on the upper end of the casing is a guide bearing 23 and extending therethrough is a rod 24, which is secured to the head member 21. Adjustably mounted in the guide bearing 23 and surrounding the rod 24 is an adjusting nut 25, and interposed between said nut and the head member 21 70 is a coil spring 26. Also mounted on the upper end of the casing C is a guide bracket 27 and a bearing bracket 28, and pivotally mounted in the bearing bracket as at 29 is a lever 30. This lever engages the upper end of the rod 24 and is moved thereby. Forming a connection between the lever 30 and the air damper 6 is a link 31, and forming an adjustment between the lever 30 and the rod 24 is a screw 32. 75

Formed exterior of the compressible flexible tube 20 is a chamber 33, and connecting said chamber with the pipe 7 is a pipe 34. This pipe maintains an oil pressure in the chamber 33, said pressure conforming to the pressure in the pipe 7, that is, increased oil pressure in pipe 7 will produce increased pressure in the chamber 33 and conversely a decrease therein when the pressure in the pipe 7 is lowered, and as the tube 20 is flexible and compressible it can readily be seen that it will be slightly compressed with an increase in the oil pressure, and that it will correspondingly expand when the oil pressure is lowered. Such expansion or contraction of the tube 20 is transmitted by the head member 21 and the rod 24 to move the lever 30 and it is in turn transmitted through the link 31 to the damper 6 which is turned and thereby opened or closed. Lowering of the 105 oil pressure in the chamber 33 under a small fire permits the tube 20 to expand. This expanding movement is transmitted to partially close the damper 6, thereby decreasing the volume of air passing through 110 the blower and delivered to the furnace when a small fire is burning. Increase of pressure in the chamber 33 will compress the tube 20 and thereby transmit a movement which will open the damper 6 and correspondingly increase the volume of air admitted to the blower and discharging into the furnace. A constant proportion of air and fuel is therefore maintained and it is 115 automatically regulated by variation of oil pressure in the pipe 7 as this is directly connected with the automatic regulator C. If it is desired to open and close the damper door shown at 40 in unison with the damper 6, it is possible to accomplish it 120 by attaching an arm 41 and a chain 42, said chain being connected at one end with the lever 30 and at its opposite end with the crank arm 41. Both air controls employed 125 in connection with the furnace front may 130

therefore be simultaneously operated or independently operated and their movements may furthermore be regulated by means of the adjusting screw 32.

5 The tension of the spring 26, as previously stated, may be varied by means of the adjusting nut 25. This usually remains undisturbed and is only adjusted when the pressure in the pipe line 7 is increased or decreased.

10 From the foregoing description it can be seen that I have provided means actuated by the steam pressure in the boiler for varying the pressure of the oil delivered to the 15 burner. Secondly that I have provided means actuated by said variation in oil pressure for automatically controlling the volume of air delivered to the furnace, said air volume being automatically maintained so 20 that a fixed proportion of fuel and air is delivered at all times.

25 While the construction of the regulator shown in Fig. 4 is more or less specific, I wish it understood that variations in design and proportion may be resorted to within the scope of the appended claims, further that the materials and finish of the several parts employed may be such as the experience and judgment of the manufacturer may 30 dictate or various uses may demand.

Having thus described my invention, what I claim and desire to secure by Letters Patent is—

1. The combination with a boiler and a 35 furnace, of an oil burner for the furnace, means for delivering oil under pressure to the burner, means actuated by the steam pressure in the boiler for varying the pressure of oil delivered to the burner, and means 40 actuated by variations in the oil pressure for automatically varying air flow through the furnace.

2. The combination with a boiler and furnace, of an oil burner for the furnace, 45 means for delivering oil under pressure to the burner, a damper adapted to regulate air flow through the furnace, means actuated by the steam pressure of the boiler for varying the pressure of the oil delivered to the 50 burner, and means actuated by variations in the oil pressure for automatically changing the position of the damper.

3. The combination with an air regulating damper in a boiler and furnace and a 55 burner for the furnace, means for delivering oil under pressure to the burner, means for varying the pressure of the oil as the steam pressure in the boiler changes, and means actuated by variations in the oil pressure 60 for automatically changing the position of the damper.

4. The combination with a boiler and a 65 furnace, of an oil burner for the furnace, means for delivering oil under pressure to the burner, a damper adapted to regulate air

flow through the furnace, a valve interposed between the burner and the means for delivering oil under pressure thereto, a steam actuated diaphragm adapted to open and close said valve, and means for partially 70 opening and closing the damper in unison with the valve.

5. The combination with a boiler and a furnace, of an oil burner for the furnace, means for delivering oil under pressure to 75 the burner, a damper adapted to regulate air flow through the furnace, a valve interposed between the burner and the means for delivering oil under pressure thereto, a steam actuated diaphragm adapted to open and 80 close said valve to vary the pressure of the oil delivered to the burner, and means actuated by the variations in the oil pressure for automatically changing the position of the damper.

6. The combination with a boiler and furnace, of an oil burner for the furnace, means for delivering oil under pressure to the burner, a valve adapted to open and close the flow of oil to the burner, a by-pass valve 90 cooperating therewith permitting a reduced flow of oil to the burner, a diaphragm actuated by boiler pressure connected with the first named valve to open or close the same, a damper for admitting air to the furnace, 95 and an automatic regulator cooperating with the diaphragm to partially close the damper when the diaphragm valve is closed and to practically open the damper when the valve is open.

7. The combination with a boiler and furnace, of an oil burner for the furnace, means for delivering oil under pressure to the burner, a valve adapted to open and close the flow of oil to the burner, a by-pass valve 105 cooperating therewith permitting a reduced flow of oil to the burner, a diaphragm actuated by boiler pressure connected with the first named valve to open or close the same, a damper for admitting air to the furnace, 110 an automatic regulator cooperating with the diaphragm to partially close the damper when the diaphragm valve is closed and to practically open the damper when the valve is open, and manually actuated means for 115 changing the position of the damper independent of said automatic regulator.

8. The combination with a boiler and furnace, of an oil burner for the furnace, a pipe for delivering oil under pressure to the 120 burner, said pipe receiving oil under constant pressure, a valve on said pipe adapted to open or close the flow of oil therethrough, a diaphragm actuated by the steam pressure in the boiler for opening or closing the 125 valve, a by-pass valve cooperating therewith permitting a reduced flow of oil through the pipe to the burner, a damper for admitting air to the furnace, and means automatically actuated by the pressure of the oil 130

delivered to the burner for changing the position of the damper as the oil pressure increases or decreases.

9. The combination with a boiler and furnace, of an oil burner for the furnace, a pipe for delivering oil under pressure to the burner, said pipe receiving oil under constant pressure, a valve on said pipe adapted to open or close the flow of oil therethrough,
- 10 a diaphragm actuated by the steam pressure in the boiler for opening or closing the valve, a by-pass valve cooperating therewith permitting a reduced flow of oil through the pipe to the burner, a damper for admitting air to the furnace, means automatically actuated by the pressure of the oil delivered to the burner for changing the position of the damper as the oil pressure increases or decreases, said means comprising
- 15 a casing, a flexible tube within the casing, a chamber formed between the casing and said tube with the oil delivering pipe, and means for transmitting movement of the flexible tube when extended or contracted by variations in oil pressure to change the position of the damper.
- 20 25 10. The combination with a boiler and furnace, of an oil burner for the furnace, a pipe for delivering oil under pressure to the burner, said pipe receiving oil under constant pressure, a valve on said pipe adapted to open or close the flow of oil therethrough, a diaphragm actuated by the steam pressure in the boiler for opening or closing the
- 30 35 valve, a by-pass valve cooperating there-

with permitting a reduced flow of oil through the pipe to the burner, a damper for admitting air to the furnace, means automatically actuated by the pressure of the oil delivered to the burner for changing the position of the damper as the oil pressure increases or decreases, said means comprising a casing, a flexible tube within the casing, a chamber formed between the casing and said tube connected with the oil delivering pipe, means for transmitting movement of the flexible tube when extended or contracted by variations in oil pressure to change the position of the damper, a second damper for admitting air to the furnace, and means for moving it in unison with the first named damper.

11. The combination with a boiler and a furnace, of a rotary burner for the furnace, the same having air delivery means co-acting therewith, means for delivering oil under pressure to the burner, means actuated by the steam pressure in the boiler for varying the pressure of the oil delivered to the burner, and means actuated by the variations in the oil pressure for varying the volume of air admitted to the burner.

In testimony whereof I have hereunto set my hand in the presence of two subscribing witnesses.

WILLIAM R. RAY.
